KNOCK OVER BIT FOR KNITTING MACHINES

Emile John Welffens, Fallowfield, England, assignor to Harcovo Societe Anonyme, Geneva, Switzerland, a company of Switzerland

Application January 6, 1931, Serial No. 506,859, and in Great Britain January 28, 1930

7 Claims. (Cl. 66—109)

The present invention relates to improvements in or relating to knock-over bits for knitting machines, particularly but not exclusively for circular knitting machines.

5 One of the objects of the present invention is to provide an improved form of knock-over bit which does not require the provision of a special slot for its location on the machine.

A further object of the invention is to provide 10 a knock-over bit which is capable not only of serving the usual purpose of assisting in drawing the loops during the process of knitting, but also of serving as a guide and a separator for a warp thread to be incorporated in the knitted fabric, 15 as a means for assisting to lay a weft thread likewise to be incorporated in the fabric alternately above and below the knitting needles, as a means for retaining the knitted fabric in position when used in a horizontal needle bed knitting inter- 20 nally or externally and as a means for assisting the knitting thread into engagement with the needle hook.

According to the present invention I provide a knock-over bit for knitting machines having a 25 relatively thick base or tail portion adapted to engage on each side with adjacent jacks when in the machine and a working head portion reduced in thickness so as to give the necessary clearance for the needles.

30 The working head of the knock-over bit is preferably of a depth somewhat greater than is usual and is preferably specially shaped so that it can perform the several functions enumerated above. A slot is provided for guiding and retaining the warp thread. The knock-over bit may be constructed from a single piece of metal or it may be built up of several pieces which may be secured together in any desired manner.

In order that the invention may be well understood, a preferred embodiment thereof will be described by way of example only and with reference to the accompanying drawing in which:

Figures 1, 2 and 3 are side elevations of portions of a built up knock-over bit embodying the 45 present invention.

Figure 4 is an end elevation of the knock-over bit.

Referring to the drawing, the bit is a built up structure consisting of five laminae. A central 50 lamina or distance piece 2 extends throughout the whole length of the bit and two laminae 1 of steel which are shaped at their upper portions to form the working head 4 of the bit are disposed one on each side of the central distance piece 2. On either side of the composite struc-

ture made up of these three pieces are two outer laminae or distance pieces 3, which do not extend all the way to the top of the bit but terminate short of the working head 4 so as to allow clearance for the needles between the working heads 60 of consecutive bits. The three distance pieces 2 and 3, 3 may be made of any suitable material such for example as steel or hard brass. The five pieces which together constitute the knock-over bit are secured together in any suitable manner 65 such for example as by riveting, welding, soldering or sweating. In the embodiment illustrated holes or slots 5 and 6 are provided in the distance pieces 2 and 3 respectively. These holes or slots are filled with solder and then the five pieces are 70 put together and heated whilst being pressed together, so that the solder flows and effectively binds the pieces together. The tail portion 7 of the bit is inclined at a suitable angle to the upper portion 8 which carries the head 4 so that 75 the upper portion 8 will be vertical when the bit is in position in the machine. The working head 4 of the bit consisting essentially, as aforesaid, of two laminae of steel 1, has a forward extension 9 to the extremity 10 of which the top of 80 the head slopes downwardly and forwardly. The extremity 10 is rounded and the underside 11 of the extension slopes in a gradual convex curve backwards and downwards towards the front vertical edge 12 of the part 8. Where the lower edge 85 11 joins the front vertical edge 12 is a recess or slot 13. It will be seen that when a weft thread or a knitting thread is caught by a needle hook it is forced to descend and follows the top sloping edge of the extension 9, passes round the extremity 10, follows the lower edge 11 and finally enters the recess or slot 13, which retains the thread below the needles as and when necessary.

The recess or slot 13 lies slightly below the top 90 of the fabric being knitted and therefore assists in retaining the fabric in position when the needles are moved forward for the next stitch.

The bits may be secured to the needle bed in any desired manner such as by means of clamping plates which grip the tails of the bits either directly or through suitably interposed packing. The clamping plates are preferably shaped and arranged so that as they are tightened they tend to force the tails of the bits into engagement 100 with two locating surfaces at right angles to one another. In the embodiment illustrated a step 14 is formed in the rear edge of the bit to assist positioning. Each clamping plate is adapted to retain a number of bits in position the number 110

varying according to the gauge of the machine and therefore the width of the bits.

Whilst in the foregoing a preferred embodiment of the invention has been described it is to be understood that various modifications may be made without departing from the scope of this invention.

I claim:—

1. A knock-over bit for knitting machines comprising two laminæ spaced apart by a central lamina and shaped at the top, to form a working head having a forward extension and a recess at the base of said extension for retaining the threads below the needles after a stitch, and two outer laminæ which terminate below the working head, said laminæ being secured together to form a unit.

2. A knock-over bit for knitting machines comprising two laminæ spaced apart by a central lamina and shaped at the top to form a working head having a forward extension and a recess at the base of said extension for retaining the threads below the needles after a stitch, and two outer laminæ which terminate below the working head, a step being provided in the rear edge of the jack to assist in positioning in the machine, all of said laminæ being united into a unitary structure.

3. A composite unitary knock-over bit for knitting machines comprising a plurality of laminæ permanently fixed together of which the lamina on one side does not extend throughout the full length of the bits but terminates short of the head portion thereof so that a relatively thick tail portion is provided adapted to engage on each side with adjacent bits when in the machine, the head portion being formed for retaining a warp thread mid-way between two adjacent needles when the bit is in the machine.

4. A composite unitary knock-over bit for knitting machines comprising a plurality of laminæ secured together of which the laminæ on both sides do not extend throughout the full length of the knock-over bit but terminate short of the

45

head portion thereof so that a relatively thick base or tail portion is provided adapted to engage on each side with adjacent bits when in the machine, the head portion being shaped for retaining a warp thread in position mid-way between two adjacent needles when the bit is positioned in the machine.

5. A composite unitary knock-over bit for knitting machines comprising two laminæ spaced apart by a central lamina and shaped at the top to form a working head having a forward extension and a recess at the base of said extension for retaining the threads below the needles after a stitch and two outer laminæ which terminate below the working head, the head portion being shaped for retaining a warp thread midway between two adjacent needles when the bit is in the machine.

6. A composite knock-over bit for knitting machines comprising two laminæ spaced apart by a central lamina and shaped at the top to form a working head having a forward extension and a recess at the base of said extension for retaining the threads below the needles after a stitch and two outer laminæ which terminate below the working head a step being provided in the rear of the jack to assist in positioning in the machine and the working head being shaped for retaining a warp thread midway between two adjacent needles when the bit is in the machine, said laminæ being secured together into a unitary structure.

7. A composite knock-over bit for knitting machines comprising two laminæ spaced apart by a central lamina and shaped at the top to form a working head having a forward extension and a recess at the base of said extension for retaining the threads below the needles after a stitch and two outer laminæ which terminate below the working head and serve as active supports for the sliding needles when the bit is in the machine, said laminæ being rigidly united into a unitary structure.
